Patented Apr. 3, 1917.

UNITED STATES PATENT OFFICE.

EMILE JEAN JULES SALMSON, OF BILLANCOURT, FRANCE, ASSIGNEE TO SOCIETE DES
MOTEURS SALMSON (SYSTEME CANTON-UNNE), OF BILLANCOURT, FRANCE.

MOUNT FOR MAGNETO-DISTRIBUTERS.

1,221,607.

Specification of Letters Patent.

Patented Apr. 3, 1917.

Application filed March 27, 1916. Serial No. 87,142.

To all whom it may concern:

Be it known that I, EMILE JEAN JULES SALMSON, citizen of the Republic of France, residing at 9 Avenue des Moulineaux, Billancourt, Seine, in the Republic of France, have invented new and useful Improvements in Mounts for Magneto-Distributors, of which the following is a specification.

This invention has for its object to provide an improved mount for the distributors of magnetos, more particularly ignition magnetos of internal combustion engines.

The essential features of the improved mount are such that it allows of a very easy adjustment of the whole distributor, and of its immediate removal and replacement for the purpose of inspecting or repairing the magneto, preventing the short-circuits which so frequently occur and which are due to the settlement of dust arising from the wear and tear of the contacts on the distributor body and the rotary carbon brush holder. Further, the perfect insulation of the armature relatively to the safety discharge device, prevents the occurrence of sparking in the neighborhood of the armature and the deterioration of the latter which is otherwise always the case.

This invention will now be more particularly described with reference to the accompanying drawings which illustrate one constructional example of the invention.

In these drawings:

Figure 1 is a longitudinal section of the general arrangement of the improved mount, and

Fig. 2 is a cross section on the line *a—a* of Fig. 1.

As shown, 1 is a block of ebonite generally cylindrical in shape, constituting a rotary carbon brush holder. It is pierced at its center with a blind hole in which is situated a contact terminal 2 for the secondary circuit, which is in contact with a terminal carried by the body of the distributor. The distributor is shown in dot and dash lines which are likewise employed to indicate the framing of the magneto and the ball bearings by means of which the whole structure revolves on the framing. The contact terminal 2 is connected to the revolving current-distributing brush 3 which is constituted by a screw-threaded nickel stem fitted in a metal part 4. This metal part 4 has an ex-

which is screwed into the contact terminal 2 for the purpose of holding the latter in place, and of establishing the electrical connection with the brush. The flat end of the stem 3 is suitably fluted and it is adapted to revolve at a short distance from the contact pieces of the distributor body.

The ebonite block 1 is fitted into a supporting socket 5 part of which is constituted by a circular cup-shaped member 6 to which the block is fixed by means of small screws 7. The other part of the socket 5 consists of a cylindrical axle-shaped member 8 serving for the purpose of centering the socket in the shaft 9 which is driven by means of a toothed wheel 10 from the main shaft of the magneto. The socket member 8 is held in place on the shaft 9 by means of a steel rod 11, one end of which is screwed and pinned in the socket member 8 and the other end of which carries a coiled spring 12 held in place by a suitably shaped washer 13 and a pin 14. The socket is driven by the shaft 9 through the medium of a flat key 15 extending through both parts.

A collar 16 mounted on the shaft 9 serves by variation of its thickness, for the purpose of adjustment of the parts at the time of erection of the apparatus; it carries a pointed arm 17 situated opposite the brush 3. In order to enable the two parts to face each other, a circular segment is removed from the cup-shaped member 6 as shown in Fig. 2. The collar 16 serves as a safety discharge device, any excessive voltage being discharged by means of sparks between the pointed arm 17 and the brush. The space between the two parts is suitably adjusted at the time of erection. This arrangement prevents the occurrence of sparking in the interrupter of the winding as would otherwise be the case, and it thus prevents any excess voltage from damaging the apparatus in any way.

Owing to the provision of the spring 12, the entire apparatus has a certain amount of elasticity, so that while assuring a perfect contact of the central terminal—upon which a spring carbon brush carried by the distributor body is constantly pressing—it prevents the comparatively frequent breakage of the latter which would otherwise occur. Further, since the rotary carbon brush holder is accurately centered, no transverse displacement thereof can occur, and since the carbon brush supplying the secondary

current to the central terminal can be regulated with a very slight pressure, the wear and tear of the revolving parts is reduced to a minimum. Consequently, very little 5 dust is produced which by settling upon the distributor body and the rotary carbon brush holder, is the habitual cause of short-circuiting.

10 The simplicity of the apparatus allows also an easy adjustment, and very quick removal and replacement of all the parts.

Having now described my invention, what I claim as new and desire to secure by Letters Patent is:

15 1. A mount for magneto distributors comprising a revolving brush holder, a supply contact terminal for the secondary current provided in said brush holder, a driving shaft, a socket in which is centered the 20 brush holder and which in turn is centered in the driving shaft against which it is pressed elastically, a key locking the socket and driving shaft together, and a collar arranged between the framing and the socket, 25 substantially as described and for the purpose set forth.

2. A mount for magneto distributors comprising a revolving brush holder, a supply contact terminal for the secondary current 30 provided in said brush holder, a driving shaft, a socket in which is centered the brush holder and which in turn is centered in the driving shaft, said socket having a circular segment cut away opposite the brush, a key 35 locking the socket and driving shaft together, and a collar arranged between the framing and the socket and provided with a pointed arm situated opposite the brush, substantially as described and for the purpose set forth.

40 3. A mount for magneto distributors comprising a revolving brush holder pierced at its center with a blind hole, a contact terminal

50 for the secondary current arranged in said blind hole, a brush formed of a nickel stem fluted at its flat end and screwed into the contact terminal for the purpose of holding the latter in place, said brush being mounted so as to revolve at a short distance from the contact pieces of the distributor body; a driving shaft, a socket in which is centered the brush holder and which in turn is centered in the driving shaft, said socket having a circular segment cut away opposite the brush, a key locking the socket and driving shaft together, and a collar arranged between the framing and the socket and provided with a pointed arm situated opposite the brush, substantially as described and for the purpose set forth.

45 4. A mount for magneto distributors comprising a revolving brush holder, a supply contact terminal for the secondary current provided in said brush holder, a driving shaft, a socket formed of a cup shaped member with a cylindrical central extension inserted into the driving shaft, said socket having a circular segment cut away opposite the brush, a key locking the socket and driving shaft together, a collar arranged between the framing and the socket and provided with a pointed arm situated opposite the brush, a rod pinned at one of its ends in the central extension of the socket, a washer pinned at the other end of said rod, and a 55 coiled spring bearing against said washer and against the driving shaft, substantially as described and for the purpose set forth.

50 In testimony whereof I have signed my name to this specification in the presence of two subscribing witnesses.

EMILE JEAN JULES SALMSON.
